DESIGN FOR A FREEZING UNIT

Morris E. Miller, Canton, Ohio, assignor, by
mesne assignments, to The Miller Industries
Company, Incorporated, Richmond, Va., a cor-
poration of Virginia

Application October 10, 1936, Serial No. 65,252

Term of patent 7 years

To all whom it may concern:

Be it known that I, Morris E. Miller, a citizen
of the United States, residing at Canton, in the
county of Stark and State of Ohio, have invented
a new, original, and ornamental Design for a
Freezing Unit, of which the following is a spec-
ification, reference being had to the accompanying
drawing forming part thereof.

Fig. 1 is a top plan view of a freezing unit
showing my new design;

Fig. 2 is a side elevation thereof; and

Fig. 3 is a front elevation thereof.

The design of the unit is characterized by pro-

viding on its opposite side walls and opposite end
walls vertical ribs parallel and adjacent to the
corners thereof, connecting these ribs along the
opposite side walls by horizontal ribs and pro-
viding above the upper horizontal rib a plurality
of relatively spaced horizontal ribs which encir-
cle the side and end walls of the unit, the vertical
and horizontal corners along the sides, ends and
top of the unit being rounded, as shown.

I claim:

The ornamental design for a freezing unit, as
shown and described.

MORRIS E. MILLER.
